UNITED STATES PATENT OFFICE

WILLIAM A. VOLLMER, OF KENOSHA, WISCONSIN, ASSIGNOR TO SIMMONS COMPANY,
OF KENOSHA, WISCONSIN, A CORPORATION OF DELAWARE

TIP

Application filed April 10, 1924. Serial No. 705,451.

This invention relates to tips or casters and sockets for mounting the same in or on the legs of chairs or other articles of furniture and has for its primary object to provide a device of this character which is strong and durable in construction, attractive in appearance, and may be cheaply and economically manufactured.

The many other objects and advantages 10 of my invention will be better understood by reference to the following specification when considered in connection with the accompanying drawing illustrating certain selected embodiments thereof, in which:—

15 Fig. 1 is a top plan view of the tip or caster.

Figs. 2 and 3 are sectional views of the tip or caster shown in Fig. 1, illustrating an economical method of making the same.

20 Fig. 4 is an elevation of the tip or caster and socket.

Fig. 5 is a section on the line 5—5 of Fig. 4.

Fig. 6 is a section on the line 6—6 of Fig. 4.

25 Fig. 7 is an elevation of the tip or caster mounted in a modified form of socket.

Fig. 8 is the same as Fig. 7, bottom plan view, and

Fig. 9 is a section on the line 9—9 of Fig. 7.

Referring to the drawing and particularly to Figs. 1 to 6, inclusive, the tip 10 includes a mounting member in the form of a substantially cup-shaped sheet metal shell 11 provided with an outwardly projecting rim flange 12, a plug or cushion 13 of felt or other suitable material, and a fastener 14 for attaching the pad to the shell. This shell is provided with a centrally located perforation 15 to admit the fastener 14. The fastener in the present embodiment is of the rivet type having a split end as at 16. The pad or cushion 13 is preferably centrally perforated as at 17. In assembling the tip, the cushion 18 is placed in the shell and the fastener inserted as in Fig. 2. A tool, as 18, having a wedge-shaped end is then inserted in the perforation 17 and forced against the split end of the fastener, spreading the same, as indicated in Fig. 3. The prongs of the fastener

are embedded in the body of the cushion and permanently retain the same within the shell.

The rim flange 12 on the outer end of the mounting member 11 is preferably formed so as to provide a smooth, outwardly facing portion adapted to engage the floor or other supporting surface when the cushion 13 is worn away, thereby permitting the article to which the tip is attached, to be slid across such surface without scratching or marring the same, even though the cushion member is no longer effective to support the article.

As shown in the drawings, the flange is preferably bent so as to form an outwardly facing convex surface (but any smooth, cornerless surface, that is, any surface free from sharp edges, will do).

A socket, as 20, is provided to receive the tip and enable the same to be mounted in the base of the leg of a chair or other article of furniture. This socket comprises a bottom plate 21 provided with a central opening 19 surrounded by a downwardly depending annular flange 22, and a sheet metal stamping. The stamping comprises oppositely disposed side members 24 integrally connected at their top as 25. These side members preferably snugly fit within the base of the leg 24' of the chair and are retained therein by friction.

The socket 20 is particularly intended for use in a chair leg of substantially rectangular cross-section and the plate 21 forms a complete closure for the base thereof. The stamping is preferably disposed diagonally of the plate 21 and the portions of this plate adjacent the corners are notched, as at 26, to admit the substantially V-shaped side members 24. The bottom edge portions of these members are folded upon the under face of the plate as at 27. The portions of the members 24 directly above this plate are preferably bent inwardly substantially upon the upper face of the plate as at 28. This forms a shoulder upon which the base of the chair leg rests. This socket construction prevents any rotation of the bottom plate within the side members and possesses strength and durability. The tip 10 is pressed upwardly into the opening 19 in the plate 21 and the flange 22 fits about the

bowl portion of the tip. The edge of this flange rests on the rim flange 12 of the tip. The rim flange of the tip serves to limit inward movement; i. e., positions the tip in the aperture 19 of the base plate part of the socket. Each of the side members 24 is preferably perforated or cut away, as at 29, to facilitate the bending of these members and prevent the formation of a corner at this point.

Referring to Figs. 7 to 9 inclusive, the socket 30 is of the sloping leg type. This particular embodiment is made in one piece, the bottom plate 31 being integral with the side members 32 which are struck up therefrom. The upper ends of these side members abut at 33. The plate 31 is provided with a central opening 34 to receive the tip 10 and this opening is surrounded by an externally projecting annular flange 36 adapted to fit about the tip in the same manner as the flange 22 in the previous embodiment. In this embodiment, the side members of the socket extend from the side edges of the bottom plate. The socket is open at the front and rear except for inwardly bent flanges 37 which preferably contact with the corresponding walls of the chair leg 38. These walls respectively rest on the projecting portions 39 and 40 of the plate 31 when the socket is inserted in the base of the leg.

In the embodiment of my invention which I have selected to illustrate the principles thereof, the sockets have been shaped to fit a leg of rectangular cross-section but it is obvious that this shape would be varied for other forms. As soon as a tip becomes worn, it may be readily removed from the socket and replaced by a new one. The embedding of the inner end of the fastener in the portion of the cushion lying within the shell of the tip prevents this fastener from coming in contact with the floor.

I claim as my invention:

1. The combination with a hollow leg, of a tip, and a tip socket snugly fitting within the base of said leg, said socket comprising a substantially rectangular base plate provided with an opening to receive and fit said tip, and an inverted substantially U-shaped member disposed diagonally of said plate and having its extremities folded about the corners thereof to connect said plate and said member, the edge portions of said plate adjacent the corners being notched to receive said extremities.

2. The combination with a leg having a recess in its base, of an axially vertical shell open at its lower end and having at said end an outwardly extending rim flange, a tip in said shell and projecting downwardly therefrom, a socket comprising a base plate provided with an opening to admit and frictionally hold said shell, the part of said plate surrounding the opening being supported by

said rim flange and an inverted U-shaped member having its extremities connected to said plate and adapted to frictionally engage the walls of said recess and retain said socket in position.

3. The combination of a hollow leg, a socket therein comprising a base plate provided with an aperture, side members secured to said base plate and extending upwardly therefrom and adapted to frictionally engage the inside of the walls of said leg, a shell seated in said aperture and frictionally engaging the edge of the plate around said aperture whereby the shell is retained in said base plate so as to be removable and replaceable, means for positioning the shell in said aperture and a tip of relatively soft material seated in said shell and projecting downwardly therefrom.

4. In combination with a leg having a recess in its base, a socket comprising a base plate provided with an opening and having a depending flange surrounding said opening, side members secured to said base plate and extending upwardly therefrom and adapted to frictionally engage the inside of the wall of said leg, and a tip seated in the opening in said base plate and comprising a shell fitting in said opening and having an outwardly projecting rim flange adapted to be seated against said depending flange on said base plate and a cushion seated in said shell and projecting therefrom sufficiently to normally prevent contact between the lower end of said shell and the floor.

5. In combination with a leg having a recess in its base, a tip of relatively soft material having a rigid, laterally projecting flange intermediate its ends, a socket comprising a base plate provided with an opening to admit the part of said tip above said flange, the part of said plate surrounding the opening being seated on said flange, and arms extending upwardly from said base plate, adapted to frictionally engage the walls of said recess for holding the socket therein.

6. In combination with a leg having a recess in its base, a socket comprising a base plate provided with an opening, a plurality of arms extending upwardly from said base plate for frictionally engaging the walls of said recess for holding the socket therein, and a tip seated in the opening in said base plate and comprising a shell having a laterally outwardly projecting rim flange adapted to be seated against a portion of said plate around said aperture, and a cushion seated in said shell.

7. In a tip of the class described, the combination of a substantially cup shaped shell having a bottom wall, the latter being provided with an aperture extending therethrough, a cushion of greater length than the depth of said shell, disposed therein with

one end seated on the bottom wall of the shell and the other end projecting beyond the outer end of the side wall of said shell and provided with an aperture extending therethrough in alignment with the aperture in

5 said bottom wall, and means for securing the cushion in said shell comprising a rivet having a head seated against the outer face of the bottom wall and a split shank extending through the aperture in the shell bottom and spread within the cushion at a point intermediate the ends of the latter, the aperture in said cushion serving to permit the insertion of a tool from the outer end of the cushion for spreading said split shank.

10 8. In a tip adapted to be seated in a socket, the combination of a substantially cup shaped shell having integral side and bottom wall portions, the side wall having a rim flange integral therewith and extending laterally therefrom for engaging a part of the socket for positioning the shell therein, and said bottom wall being provided with an aperture extending therethrough, a cushion 20 of greater length than the depth of said shell, disposed therein with one end seated on the bottom wall of the shell and the other end projecting beyond the outer end of the side wall of said shell and provided with an aperture extending therethrough in alignment with the aperture in said bottom wall, and means for securing the cushion in said shell comprising a rivet having a head seated against the outer face of the bottom wall 30 and a split shank extending through the aperture in the shell bottom and spread within the cushion at a point intermediate the ends of the latter, the aperture in said cushion serving to permit the insertion of a tool from the outer end of the cushion for spreading said split shank.

35 9. In combination, a cushion tip member, and means for mounting the cushion member on the end of a leg or the like, said means including a mounting member having a recess for receiving the cushion, the cushion being of sufficient length to project beyond the outer end of said mounting member when seated in the recess, and said mounting member being provided with a smooth, cornerless, 40 downwardly facing convex rim portion adapted to engage the floor when the projecting portion of the cushion is worn away, thereby to prevent said outer end from injuring the floor surface when the cushion is so worn.

45 10. In combination, a cushion tip member, and means for mounting the cushion member on the end of a leg or the like, said means including a mounting member having a recess for receiving the cushion, the cushion being of sufficient length to project beyond the outer end of said mounting member when seated in the recess, and said mounting member being provided with a smooth, cornerless,

outwardly facing convex external peripheral flange adapted to engage the floor when the projecting portion of the cushion is worn away, thereby to prevent said outer end from injuring the floor surface when the cushion is so worn, and means for locking said cushion in said recess.

70

11. A tip for a chair leg or the like, including a cushion, and a mounting member for mounting the cushion on such leg, said mounting member comprising a cup shaped member adapted to receive the cushion, the cushion being of sufficient length to project beyond the rim of the cup shaped member for normally engaging the floor or other supporting surface, and the rim portion of said cup shaped member being bent so as to provide a smooth, cornerless, downwardly facing rim on the cup, said cornerless rim being adapted to engage the floor when the projecting portion of the cushion is worn away, thereby to permit the article to which the tip is attached, to be slid across the floor without injuring the same, even though the said cushion is so worn away that it is ineffective to support the load of the article on which it is mounted.

75

12. The combination with a hollow leg, of a tip comprising a cup-shaped member having a laterally outwardly projecting rim flange and a cushion seated in said cup, and a socket for mounting said tip on the base of said leg, said socket comprising a base plate provided with a central opening to admit said cup member, an annular flange integral with and depending from the edge of said plate around said central opening and fitting snugly about said cup member, the base of said depending flange engaging said laterally projecting rim flange so as to position said tip with respect to said base plate, and said laterally projecting flange being of sufficient width to project beyond the face of said depending flange so as to facilitate removal of said tip from said base plate opening, and oppositely disposed side members projecting upwardly from the edge portions of said plate and adapted to snugly fit within said leg.
